[57] CLAIM

The ornamental design for a gutter down spout screen, as shown and described.

DESCRIPTION

FIG. 1 is a right front perspective of a gutter down spout screen, showing my new design;

FIG. 2 is a front elevational view, thereof;

FIG. 3 is an end elevational view, the opposite end elevational view being substantially a mirror image thereof;

FIG. 4 is a top plan view, thereof;

FIG. 5 is a rear elevational view, thereof;

FIG. 6 is a bottom plan view, thereof; and,

FIG. 7 is a left front perspective view of the article, the fragmentary representation of a gutter and a down spout assembly, shown in broken line, being included solely for illustrative purposes, forming no part of the claimed design.
